UNITED STATES PATENT OFFICE.

DAVID MATTHEW, OF PHILADELPHIA, PENNSYLVANIA.

SPARK-ARRESTER.

Specification of Letters Patent No. 12,865, dated May 15, 1855.

To all whom it may concern:

Be it known that I, DAVID MATTHEW, of the city of Philadelphia, State of Pennsylvania, have invented a new and useful 5 Improvement in the Smoke-Pipes of Locomotive Steam-Engines; and I do hereby declare that the following is a full, clear, and exact description thereof, reference being had to the accompanying drawings, making 10 part hereof.

My invention consists in having an annular space between the base of the smoke pipe, and a section extending down into the smoke box with the mouths of the exhaust 15 pipes underneath for the better relieving the smoke box of the sparks and gases.

In the accompanying drawings like letters refer to like parts and Figure 1, is a sectional front view through chimney and 20 chimney section exhaust pipes and smoke box. Fig. 2, is a side view of the chimney section removed. Fig. 3, is a top view of the chimney section removed.

A is the front part of the locomotive 25 boiler showing the flues and smoke box containing the chimney section R. D, D, is the exhaust pipes, I is the chimney.

When bituminous coal or other heavy 30 fuels is used and the sparks would remain in the smoke box; in order to cause the sparks to ascend from the smoke box into the chimney and become arrested by the apparatus I extend a section of the chimney down into the smoke box so that its open 35 end or mouth shall be near to the sparks that lie in the bottom of the box and so that this chimney section shall there stand directly over the mouths of the exhaust pipes and comes down within 4 inches of their 40 level, the exhaust pipes presenting their mouths at the lower opening of the chimney section directed upward and discharge the exhaust steam up the chimney. This chim-

ney section thus extended into the smoke box and coming down to within 4 inches of 45 the exhaust pipes by its position and the current caused by the exhaust, draws up the sparks that would otherwise be left in the smoke box in an ignited state and injure it and obstruct the lower flues. 50

The chimney section R is extended down in the smoke box leaving an annular space of 2 inches between it, and the upper chimney I and the exhaust pipes do not pass through the sides of this chimney section to discharge into it, as this would obstruct the draft, but present their mouths to its lower end and are within 4 inches and exhaust up it. This extended chimney section R Fig. 1, 2, shown in my original patent 60 granted Feby 20th 1849 by the dotted lines is necessary to be constructed with the exhaust pipes as described and shown to remove the heavy sparks from the smoke box to be arrested and consumed. 65

The following is the operation of the apparatus. When the engine is at work and the exhaust steam is passed into the chimney section from the exhaust pipes as described the sparks and heated air enter the lower 70 end R, of the chimney section I, and this current of heated air and sparks will be thrown into a spark arrester of any form or kind.

What I claim as my invention and desire 75 to secure by Letters Patent is—

The annular space between the base of the smoke pipe and the section extending down into the smoke box with the exhaust pipes underneath, arranged as, and for the pur- 80 poses herein set forth.

DAVID MATTHEW.
